UNITED STATES PATENT OFFICE.

SALMON W. PUTNAM AND WILLIAM A. FOSTER, OF FITCHBURG, MASS.

CUTTER-HEAD.

SPECIFICATION forming part of Letters Patent No. 324,041, dated August 11, 1885.

Application filed May 4, 1885. (No model.)

To all whom it may concern:

Be it known that we, SALMON W. PUTNAM and WILLIAM A. FOSTER, citizens of the United States, residing at Fitchburg, in the 5 county of Worcester and State of Massachusetts, have invented a new and useful Cutter-Head, of which the following is a full, clear, and exact description, reference being had to the accompanying drawings, forming part of 10 this specification, in which—

Figure 1 represents a vertical sectional view of a cutter-head embodying our improvements. Fig. 2 is a cross-sectional view on the line $x x$ of Fig. 1. Fig. 3 is a detail of one of 15 the cutters.

Our invention relates to cutter-heads, and, although susceptible of wide application in the mechanical art, is particularly adapted to the boring and sizing of the axle-holes in car- 20 wheels. The prominent advantages arising from its use are, greater rapidity and accuracy in the production of such work than has in most cases heretofore been achieved.

Our invention consists in the construction, 25 arrangement, and combination of devices, all of which we will hereinafter fully describe, and specifically point out in the claims.

To enable others skilled in the art to which our invention appertains to understand it, we 30 will now proceed to describe the manner in which we have carried it out.

This invention is especially designed to be used in connection with a boring-machine such as is illustrated and described in Letters 35 Patent No. 240,458, granted to Salmon W. Putnam, April 19, 1881.

The usual practice at the present time in boring car-wheels has been to use a single double-ended cutter—*i. e.*, a cutter passing 40 through the arbor itself with a “cut” on each end. In our improvement a cutter-head is af- fixed to the arbor by means of a key or equiva- 45 lent device, the said cutter-head carrying a series of cutters so arranged that they may be expanded diametrically from or toward a com- mon center either independently or collect- 50 ively, all of which will be hereinafter de- scribed.

Referring to the said drawings for a more 55 complete explanation of our invention, A re- presents the lower part of a boring-spindle,

which is provided with reduced cylindrical ends a and b , for the reception, respectively, of a hollow cylindrical sleeve, B, which carries the cutters, and a cone-shaped adjusting-sleeve, D. 55 The cylindrical reduced end a is slotted trans- versely at c , and the hollow sleeve is similarly slotted at d , while a key, C, or equivalent de- vice is adapted to engage these slots and firmly 60 secure the cutter-head to the boring-spindle. 65 The extreme lower end of the boring-spindle A has a threaded perforation, e , adapted to receive a screw, E, provided with collars f and g , which engage the cone-shaped sleeve D, and 70 adjust the cutters toward or from their com- mon center. The outer end of the screw may be squared, to better facilitate its operation. The cylindrical hollow sleeve B is provided 75 with an interior shoulder, h , which abuts against the shoulder a' , formed by the reduced end b , and the inner surface of the hollow sleeve at its lower end is tapered and cor- 80 responds, approximately, to the size and config- 70 75 80 85 90 95 100 uration of the adjusting-sleeve D. This lower portion of the hollow sleeve is slotted at l , and in these slots are placed the radiating cutters m , preferably six in number, their inner ends bearing against the cone-shaped sleeve, which adjusts them toward or from their common center, while their outer ends are beveled to 80 form suitable cutting-edges. Through the lower end of the cylindrical sleeve B is a series of screws, F, which securely hold the cutters in any position desired.

From the foregoing description it is mani- 85 fest our cutter-head has many advantages. By the use of our cutter-head we have (by choice) six cutters, which enable us to increase the rate of feed to three-fourths to one revolution, and still each cutter will be required to sus- 90 tain but one-eighth cut. It will thus be seen that in a given time we can do one-third more work than has hitherto been accomplished, and without forcing our cutters beyond a point of endurance. Again, by arranging our 95 cutters so that they may be expanded as one or all of them become worn or dulled, we can take the cutters out separately, or take the cutter- head off entire, expand the cutters, (or cutter,) 100 resharpen them on a simple grinding arrange- ment, and replace the cutter-head on the ar- bors, and it can cut the original size. The cut-

ters may be sharpened in this way many times. The advantages arising from this "expansion" system are, that with one set of cutters it enables various sizes of holes to be bored, this 5 feature being valuable in repairing car-wheels and car-axles, as required in railroad and locomotive shops; also, when car-wheels are hard or unevenly "cored," it is desirable to first take a "roughing-out" cut, leaving but 10 a small amount of stock to be removed for the following finishing "chip." In this case, for the first cut, the cutters are contracted, (by turning the screw which operates the conical sleeve in the cutter-head,) and after the roughing-out cut is taken they are then expanded 15 for the finishing size.

The cutter-head as shown represents all the cutters as cutting on the same plane. We, however, deviate from this plan in some cases by 20 having one or more of the cutters located to cut somewhat in advance of the other cutters, for the purpose of having the "leading" cutter remove the "scale" from the metal, thereby prolonging the life of the cutting-edges of 25 the "sizing" or finishing cutters. This may be accomplished by means of the screw r , which enters the base of the cutter and bears against the adjusting-sleeve. The advancing

cutter (which is the first one dulled) may be taken out by itself and resharpened on an ordinary grindstone. 30

Having thus described our invention, what we claim as new, and desire to secure by Letters Patent, is—

1. The combination, with the arbor and a 35 cutter-head detachably secured to the arbor, of suitable adjustably-secured radial cutters, substantially as herein described.

2. In combination with the arbor and cutter-head, a series of cutters which admit of a 40 radial adjustment from a common center, both universally and independently, substantially as herein described.

3. The combination, with the arbor and cutter-head, of cutters attached to said cutter-head and means, substantially as described, 45 whereby one or more of the cutters may be adjusted to cut in advance of the remaining cutters, substantially as and for the purpose described.

SALMON W. PUTNAM.
WILLIAM A. FOSTER.
